UNITED STATES PATENT OFFICE.

JAMES H. WHITEHOUSE, OF BROOKLYN, ASSIGNOR TO TIFFANY & CO., OF NEW YORK, N. Y.

DESIGN FOR A BADGE.

SPECIFICATION forming part of Design No. 16,647, dated April 20, 1886.

Application filed March 25, 1886. Serial No. 196,595. Term of patent 7 years.

To all whom it may concern:

Be it known that I, JAMES H. WHITEHOUSE, a subject of the Queen of Great Britain, and a resident of the city of Brooklyn, in the county of Kings and State of New York, have invented a new and original Design for a Badge, of which the following is a specification, reference being had to the accompanying drawing, forming part thereof.

10 This design has reference to a configuration on a badge composed in outline like the figure 7. There is contained on the surface, in the upper portion of the figure 7, ivy-leaves in relief, with stems extending down the body of the figure and terminating in the letters H and V, being ornamental in appearance.

15

In the drawing, a a are the ivy-leaves in the head of the figure 7. b is the stem. c c are the letters H and V.

I claim—

- 20 1. A design for a badge, consisting in outline of the figure 7, on the surface of which are placed ivy-leaves, a stem, and ornamental characters, as herein shown and described.
2. A design for a badge, consisting in outline of the figure 7, on the surface of which are placed ivy-leaves a a and stem b, as herein shown and described.
